United States Patent Office.

JOHN R. ROSE AND EDWARD L. CALEY, OF PHILADELPHIA, PENNSYLVANIA, ASSIGNORS TO COX, WHITEMAN & COX, OF SAME PLACE.

Design No. 2,984, dated March 31, 1868; antedated March 3, 1868.

DESIGN FOR THE DOORS OF A STOVE.

The Schedule referred to in these Letters Patent and making part of the same.

TO ALL WHOM IT MAY CONCERN:

Be it known that we, JOHN R. ROSE and EDWARD L. CALEY, of the city of Philadelphia, in the State of Pennsylvania, have invented or produced a new and original Design for Stove-Doors, of which the following is a full, clear, and exact description, reference being had to the accompanying drawing, making a part of this specification

Referring to the drawing, A B and B C represent two of the doors applied to the side plate D of a stove. The nature of our design consists of the ornamented moulding E and centre-piece F, as shown in the drawing.

What we claim as our invention, and desire to secure by Letters Patent, is—
The ornamental design for stove-doors herein set forth and shown.

J. R. ROSE,
EDW. L. CALEY.
